UNITED STATES PATENT OFFICE.

ELMER L. SCHUMACHER, OF SOUTHBRIIDGE, MASSACHUSETTS, ASSIGNOR TO AMERICAN OPTICAL COMPANY, OF SOUTHBRIIDGE, MASSACHUSETTS, A VOLUNTARY ASSOCIATION OF MASSACHUSETTS.

CASE.

Application filed December 18, 1919. Serial No. 345,776.

To all whom it may concern:

Be it known that I, ELMER L. SCHUMACHER, a citizen of the United States, residing at Southbridge, in the county of 5 Worcester and State of Massachusetts, have invented certain new and useful Improvements in Cases, of which the following is a specification.

This invention relates to improvements in 10 cases and has particular reference to a novel and improved construction of a case particularly adapted to contain an ophthalmic mounting.

One of the leading objects of the present 15 invention is the provision of a novel and improved construction of what is known as self-opening case or case in which the cover is held in closed position and when released will rise of itself, as distinguished from 20 the other known type of eyeglass cases in which the case is held in either open or closed position by a spring, but which must be manually shifted to either position as desired.

25 A further object of the present invention is the provision of a structure of this character which may be satisfactorily employed with either covered or uncovered spectacle and eyeglass cases or the like, and which 30 further will possess the advantage that the opening means are so concealed or protected that accidental striking and thus opening of the case is practically impossible and in all events improbable.

35 A further object of the present invention is the provision of a novel and improved structure for the purposes aforesaid, which shall utilize the present forms or structures of eyeglass cases of other types and shall 40 thus reduce the cost of production of my improvement as a manufacturing proposition to a minimum.

Other objects and advantages of my invention should be readily apparent by reference to the following specification taken 45 in connection with the accompanying drawings, and it will be understood that I may make any modifications in the specific details of construction shown and described 50 within the scope of the appended claims without departing from or exceeding the spirit of my invention.

Figure I represents a plan view of a case embodying my improvements.

55 Figure II represents a fragmentary sec-

tional view of one form of the securing device.

Figure III represents a fragmentary view of the structure shown in Figure II with cover raised. 60

Figure IV represents a detail view of one form of spring construction particularly applicable to the invention illustrated in Figures II and III.

In the drawings, the numeral 1 designates 65 the cover, and the numeral 2 the bottom section of an ordinary eyeglass case, the portion 2 being preferably provided with the lip 3 which extends reversely and engages beneath the lid or cover 1 to render the case more 70 dust-proof. Eyeglass cases are divided into two general classes, namely covered, or cases which have a leather or other covering material secured on the outer surface, and the uncovered case, such as silver, polished aluminum and the like. My invention is equally 75 applicable to both of these constructions, although in certain instances slight structural changes are preferably made according to the particular type of the case in 80 question.

The cover and base are hinged together as by the pintle 5 which connects the hinge ears or portions 6 of the two sections. To hold the cover, in closed position I either cut 85 integrally therefrom or secure thereto, as by welding, or riveting the depending latch member 22 adapted to interlock with the catch or keeper 11, and I preferably make use of an actuating spring, either integral 90 with or separate from the keeper member, this actuating spring being shaped to conform to the shape of the bottom or base portion 2 of the case and fit around the inner edge thereof in the U-shaped portions 13, 95 united at the front with the latch member through the integral loop 11. The rearward ends of the U-shaped members preferably fit beneath and are securely retained in position by integral ears turned down from the 100 rear upper edge of the bottom of the case and which have hitherto been provided in cases of this general external appearance to hold down a portion of the rear actuating spring. 105

In Figures II and III, I have illustrated a form of the invention, in which the inward overhanging portion of the lip or bottom 3 of the case is reversely bent or depressed as at 21 to receive and make tight joint with 110

the inturned portion 22 on the lid, this in-turned portion thus providing the keeper recess 23 to receive the latch member 11 of the spring 13, which is so shaped as to firmly 5 press toward the front of the case and to retain in position the push button 24 in the form of a cup member dropped in the slot 17 to form a closure for the slot and held in place by pressure of the spring 13 there- 10 against, providing a satisfactory member which may be pressed inwardly to release the latch and allow the cover to open the walls of the case as at 25, the sides of the slot 17 being bent to form guides for the actuating 15 member 24.

I claim:

1. In a device of the character described, the combination with a pair of hinged members, of means for swinging the members 20 apart on their hinge, a latch carried by one of the members, a keeper by the other member for locking them in closed position, a resilient control for said latch and keeper including a spring member operably associated 25 with one of said parts, and an actuating button interposed between the spring and wall of the case, the button being held in position by the pressure of the spring thereagainst.

2. In a device of the character described, 30 the combination with a pair of hinged members, of means for swinging the members apart on their hinge, a latch carried by one of the members and a keeper by the other member for locking them in closed position, 35 a resilient control for said latch and keeper including a spring member operably associated with one of said parts, and an actuating button interposed between the spring and wall of the case, the button being held 40 in position by the pressure of the spring

thereagainst, the case having a slot formed therein affording access to the button, the button being contained within the outlines of the case.

3. In a device of the character described 45 including a pair of hinged members, one of said members having an integral reversely bent edge portion forming a latch and a resilient keeper carried by the other of said members for interlocking engagement with 50 the inwardly deflected portion of the opposed member.

4. In a device of the character described the combination with a body section, of a cover hinged thereto having a reversely bent 55 front edge portion providing a keeper re-cess and a resilient keeper carried by the body member and having a portion adapted to project into the recess formed by the re-versely curved edge to secure the cover in 60 closed position.

5. In a device of the character described the combination with a body section, of a cover hinged thereto having a reversely bent front edge portion providing a keeper re-cess and a resilient keeper carried by the body member and having a portion adapted to project into the recess formed by the re-versely curved edge to secure the cover in 65 closed position, said body portion having a 70 slot formed therein and the resilient keeper having a portion projecting into and accessible through the slot for release thereof.

In testimony whereof I have affixed my signature, in presence of two witnesses.

ELMER L. SCHUMACHER.
